STOP-MOTION DEVICE FOR KNITTING MACHINES WITH LATCH NEEDLES

Hynek Luňák, Trebic, Czechoslovakia, assignor to Zapadomoravské strojírny, národní podnik, Trebic, Czechoslovakia

Filed Mar. 19, 1958, Ser. No. 722,405

Claims priority, application Czechoslovakia Mar. 25, 1957
15 Claims. (Cl. 66—157)

The invention relates to circular knitting machines operating with latch needles, and more particularly to a stop-motion device which is actuated by released needle latches and comprises a pivotally mounted feeler and two electric contacts which are arranged to co-act in a substantially closed casing.

In knitting machines of the kind mentioned very delicate needles are used and have latches pivotally mounted in the body of the needles. It is well known, that the latches of these needles are maintained in the closed position by the yarn proper during the knitting operation. When for any reason the yarn breaks, the released latch of the needle pivots outwardly. This happens particularly in circular knitting machines wherein the needles are caused to move along a circular path and the latches are subjected to the action of centrifugal force so that the latches in the absence of yarn assume a radial position. The prompt detection of such a released latch of a needle is of importance and should be followed by automatic and immediate stopping of the machine as in the case of a broken or not properly tensioned yarn. An open latch is commonly detected by a pivotal feeler member of the stop-motion device, which member, when it is engaged by a released latch of a needle, actuates electric contacts to close an electric circuit for stopping of the machine. In view of the fact that the latch, particularly of thin needles is a very delicate element, it is important that the feeler member react immediately upon its contact with a released latch without subjecting the latch to any appreciable force. Otherwise, the latch would be bent or broken when it engages the feeler member. It is therefore important that the feeler member and the switching members are so arranged that the force required for their operation, i.e. for the pivotal movement of the feeler member and for the closing of the electric circuit, should be very small and should not be able to damage the released latch. The necessary pivotal movement of the feeler member should also be as small as possible in view of the fact that the pointed end of the open latch quickly loses contact with the pointed end of the feeler member because of its movement along a circular path. Moreover, it must be possible to adjust the feeler member into the operational position, i.e. into a position very near to the latches of the needles, in a simple and accurate manner.

In a recently proposed stop-motion device actuated by released needle latches, wherein a pivotally mounted feeler member and two electric contacts are used and the feeler member is deflected when it is engaged by an open latch of a needle, the feeler member together with the movable electric contact forms a single unit, and one arm of the movable contact is arranged to lift the free end of the fixed contact, which is resiliently mounted, so that the arm of the movable contact is free to engage an opening in the fixed contact and to complete the current circuit.

The rigid connection of the movable contact with the feeler member so that they form a unit has, however, the disadvantage that the relative position of the movable and fixed electric contacts varies with the result that a tedious adjustment of the feeler member is required. The

2

lateral deflection of the feeler member causes at the same time a turning of the movable electric contact for engagement with the fixed electric contact. The movable contact must, however, be in such a position that no contact takes place between the contacts when the feeler member is in its position of readiness for operation; on the other hand, the distance between the contacts must be so small that the deflection required for the engagement of the contacts should not be too great, considering the circular path of a released needle latch.

The above mentioned drawbacks are overcome by the device according to the invention, according to a basic feature of which the movable electric contact is mounted within a casing on a pin adjacent to the fixed electric contact which is supported by the lid of the casing. A gap is formed between the head of the fixed contact and the movable contact, which gap is maintained by a tooth of a trigger pawl against which the movable contact rests. The pawl is mounted on one end of a spindle 15 the other end of which carries a connecting member which holds the feeler in its position of readiness. This position is determined by the abutment of an arm of the trigger pawl against the inner wall of the casing, and the switched-off position of the feeler member is determined by the movement of a tooth of the trigger pawl into a recess of the movable contact which has a free end projecting out of the casing. The abutment of the arm of the trigger pawl against the inner wall of the casing, and the movement of the tooth of the trigger pawl into the recess of the movable contact are actuated by a tension spring which is linked to the movable contact and to the trigger pawl and thus actuates the movements of both these members.

The invention will now be described in more detail with reference to an embodiment thereof shown in the accompanying drawings, wherein

FIG. 1 represents a perspective view of the stop-motion device actuated by released needle latches, the feeler member being shown in a position of readiness to operate,

FIG. 2 shows a vertical section along the plane *a—a* of the device of FIG. 1,

FIG. 3 is a plan view of the device of FIG. 1 without lid, showing the feeler member in its position of readiness,

FIG. 4 is a plan view of the device of FIG. 1 with the lid of the casing removed, showing the feeler member in its operating position, and

FIG. 5 is a fragmentary section along the plane *b—b* of FIG. 4.

The stop-motion device sensitive to the position of the latches of the needles consists of a feeler member 1 with a widened flat end 2 which is adapted to be engaged by released or open latches 3 of needles 4 which move on a circular path determined by the needle cylinder of a circular knitting machine. The feeler member 1 is adjustably mounted by means of a screw 6 in a connecting member 5, and it is free to carry out a pivotal movement to assume either the position of readiness I (FIG. 3) or the operating position II (FIG. 4). The connecting member 5 is fastened by means of a screw 8 to a vertical spindle 7 which is rotatably mounted within a sleeve 9 which forms an integral unit with a casing 10 fixed to the upper end of the sleeve. The sleeve 9 is adjustably mounted in a holder or support 11 so that it can be rotated about its axis and shifted in a vertical position and then adjusted in this position by means of a screw 12, whereby the whole stop-motion device can be adjusted into the required position with respect to the needles 4. The upper end of the spindle 7 projects into the casing 10 and carries, firmly connected to it, a

trigger-pawl 13 which has a form of a bell-crank lever, one arm 14 of which has at its end a tooth 15 and normally rests against the inner face of the wall 16 of the casing 10 whereby the position of readiness I of the feeler member is determined. The other arm 17 of the pawl 13 is attached to one end of a tension spring 18, the other end of which is fastened to the movable contact 19 which is provided with a recess 20 into which the tooth 15 of the arm 14 can move. The movable contact 19 is pivotally mounted on a vertical pin 21 of the casing 10 and the free end 22 of the contact 19 is insulated and passes through an opening 23 in the wall 16 and projects beyond this wall outside the casing. The casing is closed by means of a lid 24 consisting of a transparent material. The lid is fastened to the casing by means of a screw 25 and forms an insulating carrier for the fixed contact which is formed by a screw 26 and is fastened to the lid 24 by means of a nut 27 in such a manner that the head 28 of the screw can be contacted by the movable contact 19 (FIGS. 4 and 5). In this way, the lid 24 permits inspection of the mechanisms within the casing 10 without removal of the lid 24. An electric lead 29 is fastened between the lid 24 and the nut 27.

The described device operates as follows:

During the knitting of the leg of hose, for instance, when defects hardly occur, the feeler member is in its position of readiness I (FIG. 3), i.e. radially adjacent the needles 4 which move along a circle as indicated by the arrow. The movable electric contact 19 is spaced from the head 28 of the fixed electric contact 26 so that the electric circuit is interrupted. A predetermined gap x (FIG. 2) separates the movable contact 19 from the head 28 of the fixed contact 26 when the trigger pawl 13 with its arm 14 abuts against the inner face of the wall 16 of the casing 10, i.e. when the feeler member 1 is in its position of readiness I. The tooth 15 at the same time holds the movable contact 19 in position against the force of the tension spring 18.

In the case of a defect, when the latch 3 of any one of the needles 4 is in the open or released position (FIG. 4), the feeler member 1 is engaged by a latch 3 at its end 2, and is pivoted in the direction of the arrow, i.e. from the position of readiness I into the operating position II. As a result of the pivotal movement of the feeler member, the spindle 7 is caused to turn with the trigger pawl 13 attached to it. The turning movement is in a clockwise direction, as seen in FIGS. 3 and 4. The tooth 15 of the arm 14 is aligned for engagement with the recess 20 of the movable contact 19 so that the movable contact is free to turn about its vertical pin 21 and is pulled by the spring 18 against the head 28 of the fixed contact 26 (FIG. 5). Closing of the contacts completes an electric circuit, electro-magnetic circuit members, known per se, are actuated and cause an immediate stopping of the machine. After the defect has been removed, the machine is switched on again by manually moving the free insulated end 22 of the movable electric contact 19 in a direction away from the fixed contact 26 until the trigger pawl 13, the spindle 7 and the feeler member 1 can be returned by the tension spring 18 into the position of readiness I (FIG. 3).

The device according to the invention is intended mainly for use in connection with circular knitting machines with latch needles for the manufacture of seamless hosiery, but it is not limited to the manufacture of this type of articles and may be likewise used in circular knitting machines with latch needles for the manufacture of other knitted fabrics.

What I claim is:

1. In a stop-motion arrangement for a knitting machine, in combination, a support; a first contact member fixedly mounted on said support; a second contact member mounted on said support, said second member being

movable into and out of engagement with said first member for closing and opening a stop-action circuit; pivot means on said support having an axis; a feeler member mounted on said pivot means for turning movement about said axis between a first and a second angular position; a trigger member mounted on said pivot means and permanently connected to said feeler member for joint movement therewith about said axis; abutment means on said trigger member for abutment against said movable second contact member when said feeler member is in said first position thereof so as to selectively prevent movement of said second contact member into engagement with said first contact member; resilient means for urging said second contact member to move into engagement with said first contact member; and for urging said feeler member to move from said second towards said first position thereof and a plurality of latch needles each having a latch movable toward and away from an open position, each needle being mounted for movement in an arcuate path relative to said support and for abutment of said latch thereof against said feeler member when said latch is in the open position thereof during said movement of said needle, and said feeler member is in said first position thereof.

2. In an arrangement as set forth in claim 1, said feeler member and said trigger member being fixedly connected.

3. In an arrangement as set forth in claim 1, said resilient means being a resilient member having spaced portions respectively secured to said second contact member and said feeler member for urging said second contact member and said feeler member for urging said second contact member to move into engagement with said first contact member, and for simultaneously urging said feeler member to move towards said first position thereof.

4. In an arrangement as set forth in claim 3, said second contact member being movable in a predetermined direction for closing said stop-action circuit, and said feeler member having an actuating element fixedly secured thereto, said actuating element moving in a direction opposite to said predetermined direction when said feeler member moves towards said first position thereof, said resilient member permanently urging said contact member and said actuating element to move in said predetermined and in said opposite direction respectively.

5. In an arrangement as set forth in claim 1, said latch needle being movably mounted for movement of the latch of said needle in a predetermined direction and path when said latch is in the open position thereof, said feeler member projecting into said path of said open latch to be moved from the first to the second angular position thereof by engagement with said open latch.

6. In an arrangement as set forth in claim 1, said second contact member being pivotably mounted on said support and pivotable into and out of engagement with said first contact member about an axis.

7. In an arrangement as set forth in claim 6, said pivoting axis of said second contact member being substantially parallel to the axis of said pivot means.

8. In an arrangement as set forth in claim 1, said feeler member and said trigger member being fixedly mounted on said pivot means and radially projecting therefrom.

9. In an arrangement as set forth in claim 1, said second contact member having a stepped face portion opposite the abutment means on said trigger member, one of the steps of said face portion abutting against said abutment means when said feeler member is in said first portion thereof, and being urged into abutment by said resilient means.

10. In an arrangement as set forth in claim 1, said support being a casing and said contact members being enclosed in said casing.

11. In an arrangement as set forth in claim 10, manual

setting means secured to said second contact member and projecting from said casing.

12. In an arrangement as set forth in claim 1, said feeler member being fixedly mounted on said pivot means and axially adjustable thereon.

13. In an arrangement as set forth in claim 1, said trigger member being a two-armed lever, one of the arms thereof carrying said abutment means, and the other arm cooperating with said resilient means.

14. In an arrangement as set forth in claim 1, said abutment means being out of abutment against said second contact member when said feeler member is in the second position thereof.

15. In a stop-motion device for a knitting machine having a latch needle movably mounted thereon for movement of the latch of said needle in a predetermined direction and path when said latch is in the open position thereof, a casing; a first contact member fixedly mounted in said casing; a second contact member mounted in said casing, said second member being reciprocably turnable about an axis into and out of engagement with said first member for closing and opening a stop-motion circuit and having a stepped face portion; manual setting means secured to said second contact member and projecting from said casing; pivot means mounted on said casing for rotation about an axis substantially parallel to the axis of rotation of said second member; a feeler member fixedly mounted on said pivot means for turning movement about the axis thereof between a first and a second angular position, an actuating portion of said feeler member projecting from said casing and said casing being mounted on said knitting machine in such

a manner that said actuating portion of said feeler member projects into said path of said open latch for movement thereby in said predetermined direction from the first to the second angular position of said feeler member; a trigger member fixedly mounted on said pivot means and connected to said feeler member for joint movement therewith about the axis of said pivot means, said trigger member having two arms radially extending from said axis; abutment means on one of said arms for abutment against one of the steps of said face portion when said feeler member is in said first position thereof so as to selectively prevent movement of said second contact member into engagement with said first contact member, said abutment means being out of abutment against said step when said feeler member is in the second position thereof; a resilient member having spaced portions respectively secured to said second contact member and to the other arm of said trigger member for permanently urging said second contact member to move into engagement with said first contact member, and for urging said feeler member to move towards said first position thereof.
